UNITED STATES PATENT OFFICE.

SIDMOOR S. SAGER, OF BUFFALO, NEW YORK.

MULTIPLE-COUPLING PUMP FOR FRUIT JARS AND THE LIKE.

Application filed November 14, 1921. Serial No. 515,162.

To all whom it may concern:

Be it known that I, SIDMOOR S. SAGER, a citizen of the Dominion of Canada, residing at Buffalo, in the county of Erie and 5 State of New York, have invented a new and useful Improvement in Multiple-Coupling Pumps for Fruit Jars and the like, of which the following is a specification.

This invention relates to multiple coupling pumps for fruit jars and the like and particularly to pumps for effecting hermetic sealing of fruit jars and other containers; and the principal object of the present invention is to provide a device of this nature 15 which may be used to effect sealing of jars having different sizes of tops.

Another object is to produce a device of this nature which shall be simple of construction, cheap to manufacture, and highly efficient for the purpose for which it is 20 designed.

Another object is to provide a pump having a plurality of suction seats and a single suction cylinder co-operative with all of 25 the seats.

With these and other objects in view, the invention resides in certain novel features of construction and combination and arrangement of parts, the essential features 30 of which are hereinafter fully described, are particularly pointed out in the appended claims, and are illustrated in the accompanying drawing, in which:

Figure 1 is a vertical sectional view of 35 the device as applied to a large size fruit jar.

Figure 2 is a similar view of the same as applied to a small jam jar.

Like characters of reference refer to like 40 parts in all views.

In putting the pump shown in my Patent No. 1,384,780, issued July 19, 1921, on the market, it has been found that it would be desirable to have a variety of sizes of jars 45 such as shown in my Patent No. 1,356,224 issued October 19th, 1920. But in this case it would have been necessary to provide a different size pump for each size of jar, and the cost of such procedure would render it commercially undesirable. To avoid 50 this difficulty and still obtain the desired end, the present invention contemplates the combining of a plurality of pumps into a single structure.

55 Referring to the drawing in detail, the invention consists in a tubular pump casing 10

having a cap screwed on its outer end, through which passes the plunger rod 12 of the piston 13. Secured to the lower or free end of the barrel 10 is a cupped member 11 which is formed with a flange-like shoulder 14 and an apron 15 terminating in a flange 16. Mounted in the shoulder 14 and projecting therebelow is a resilient washer or seating element 17 which is removably held in its seat by a ring or annular band 18. Mounted in the flange 16 is a resilient washer or seating element 19 held in place by a ring or band 20. The rings 18 and 20 are circular in form and 60 L-shaped in cross-section.

In the drawing containers are shown at A and B and when it is desired to seal them the respective sealing seats 17 and 19 are placed in contact with the jar body and 65 the pump is operated using the cover for a valve member as described in my said prior patents. But it will be noticed that either cover may be used as the valve in the present instance, the element 17 being spaced 70 far enough above the cover when the large container is being sealed, not to interfere with the necessary slight up and down movements of the cover. While I have shown this device as applicable to two sizes 75 of jar, it will be readily understood that it may be made so as to co-operate with any desired number of different sizes of covers. I therefore do not limit my invention to the exact details of construction herein described, nor to anything less than the entire invention limited only by the appended claims.

And now having described my invention, what I claim as new and desire to secure 80 by Letters Patent is:

1. In a multiple pump for fruit jars, the combination of a pump barrel, a piston mounted for operation therein to cause entrance and exit of air from the barrel, a 100 plurality of annular elements provided with means securing them substantially around the entrance or inlet end of the barrel and excluding air from said inlet end except that air which passes through the annular 105 elements, one of these annular elements being smaller than the other and in a plane nearer the inlet end than the larger annular element, these annular elements each being provided with a clear space within and at 110 its inner surface to permit it to be seated against the outer periphery of an upward-

2
ly extending annulus on a jar's mouth while it is also seated on an upper surface of the jar's mouth, substantially as shown.

2. The structure defined by claim 1, in combination with means for removably securing each of these annular elements in such relation to one another that they can be thus fitted, respectively, to the larger

and smaller mouths of jars while retaining their positions relative to one another, substantially as shown. 10

In testimony whereof I have signed my name to this specification this 17th day of October, 1921.

SIDMOOR S. SAGER.
